CABINET WITH RACKS

Paul F. Kraeft, North Bergen, N. J.

Application November 28, 1940, Serial No. 367,513

8 Claims. (Cl. 312—176)

This invention relates to cabinets with racks. It is particularly directed to a cabinet with racks for cups, glasses, plates, bowls, and the like articles, and adapted to be placed in washing machines.

Racks of the general type described, are made of wire, and have at the bottom, a reinforcing frame of angular cross-section, and may be formed with any suitable wire partitions depending upon the articles to be placed into the rack. It is an object of the present invention to provide a cabinet for such racks having compartments into which the racks are inserted like drawers, the cabinet and racks being provided, in accordance with this invention, with cooperating means to retain the racks in partly withdrawn position, to expose a portion only of the racks, whereby articles may be withdrawn from the exposed portions or placed thereinto.

A further object of this invention is to provide in a cabinet with racks of the character described, means to permit a slight downward and forward tilting of the rack, when the rack is partially withdrawn from the cabinet, and means on the cabinet serving as stops to limit movement of the racks in fully inserted position within the cabinet, the means for retaining the racks in partially withdrawn position and in fully inserted position, also serving to hold the racks within the cabinet.

Yet a further object of this invention is to provide a rack of the character described, which is square, and a cabinet having a square compartment to receive the rack, and the rack having intermediate portions at both pairs of opposite sides thereof, to engage means at the front of the compartment, to retain the rack in partially withdrawn position, when the rack is in the compartment when any of its four sides are at the front.

Still a further object of this invention is to provide a highly improved rugged and durable cabinet and rack construction of the character described, which shall be relatively inexpensive to manufacture, easy to manipulate, and yet practical and efficient to a high degree in use.

Other objects of this invention will in part be obvious and in part hereinafter pointed out.

The invention accordingly consists in the features of construction, combinations of elements, and arrangement of parts which will be exemplified in the construction hereinafter described, and of which the scope of application will be indicated in the following claims.

In the accompanying drawings, in which is

shown one of the various possible illustrative embodiments of this invention.

Fig. 1 is a side elevational view of a cabinet with racks embodying the invention, with parts broken away and in cross-section, and showing one rack in partially withdrawn position;

Fig. 2 is a cross-sectional view taken on line 2—2 of Fig. 1;

Fig. 3 is a cross-sectional view taken on line 10, 3—3 of Fig. 1;

Fig. 4 is a cross-sectional view taken on line 4—4 of Fig. 3;

Fig. 5 is a cross-sectional view taken on line 5—5 of Fig. 1;

15 Fig. 6 is a partial, perspective view of a side wall of the cabinet showing one of the rack guides and lugs to retain the rack against movement, and

Fig. 7 is a view similar to Fig. 6, but also showing a portion of the angle frame of one side of the rack with notch engaging the lug on the guide.

Referring now in detail to the drawings, 10 designates an article embodying the invention, comprising a cabinet 11 supporting a plurality of square racks 12 for cups, glasses, plates, bowls or the like articles.

The racks 12 are of the type which may be placed in washing machines to wash the articles 30 in the rack. These racks are made of wire and have front and rear portions 13, side portions 14, a bottom portion 15, and are open at the top. Within the racks are any suitable partitions 16 to separate the glasses, bowls, dishes or other articles placed in the rack.

Each of the racks 12 is formed at the bottom thereof with a reinforcing frame of angular cross-section, comprising front and rear, symmetrically disposed portions 18, and symmetrically disposed side portions 19. The portions 18 have upwardly extending walls 18a and horizontal, inwardly extending walls 18b. The side portions 19 comprise vertical or upwardly extending walls 19a, and horizontal, inwardly extending walls 19b.

45 The walls 18b of the portions 18 are formed at the mid-portions thereof with aligned notches 20, for the purpose hereinafter appearing. The walls 19b of the portions 19 are formed with notches 21, for the purpose hereinafter appearing. The notches 20 and 21 preferably extend to the edge portions of the walls 18b and 19b, respectively.

Referring now to the cabinet 11, the same has side walls 30, a rear wall 31, a bottom wall 32, and a top wall 33c, and may be open at the front, or if desired, the front may be closed by

any suitable doors, not shown. Fixed to the inner surfaces of the side walls 30, are pairs of aligned, horizontal, guides 33 to support the racks 12, each rack being supported on a pair of aligned guide bars. The guide bars 33 may be of angular cross-section, each comprising a vertical wall 33a and a horizontal, inwardly extending wall 33b.

The walls 33b of the guide bars 33 are each formed at the front and rear with upwardly extending lugs 34 and 35. The bars 33 may be made of metal and the lugs 34 and 35 may be made by slitting the ends of wall 33b inwardly along lines parallel to the outer edge thereof, and bending the metal between the slits and said outer edge, upwardly. The distance between the lugs 34 and 35 is substantially somewhat in excess of the length of the rack 12.

It will be noted that the racks are supported on the horizontal walls 33b of the guide bars 33, and that the frame portions at the sides of the rack contact said horizontal walls. When a rack is fully inserted in the cabinet, the lugs 34 and 35 on the opposite guide bars 33 are located in front of, and at the rear of the rack, to keep the rack from sliding either forwardly or rearwardly.

The space between one pair of guide bars 33 and the next adjacent pair of guide bars is greater than the height of the rack to permit a clearance so that when it is desired to withdraw the rack, the rack may be lifted above the lug 34 and drawn out of the cabinet. When it is desired to partially withdraw the rack, the front part thereof is lifted until it clears the lugs 34, and the rack is pulled forwardly to a position where said lugs engage within the notches 21. The front part of the rack may then be tilted downwardly, as shown in Fig. 1 of the drawings, articles may then be withdrawn from the front part of the rack. In such position the guide bars above the rack contact the rear end of the rack, as shown in Fig. 1.

It will be noted that the racks may be inserted into the cabinet with either the portions 13 at the front and rear, or with the portions 14 at the front and rear, by reason of the fact that the racks are square in shape. In either position, notches 20 or 21 will be disposed at the sides to receive the lugs 34.

The combination cabinet and rack construction disclosed herein is particularly suitable for ships, the lugs 34 and 35 serving to keep the racks within the cabinet or in partially withdrawn position, even on the rough sea.

When the rack is partially withdrawn, as shown in Fig. 1, a part of the rack may be used without exposing the rear part, and furthermore, when the rack is supported in partially withdrawn position, it is firmly held in the cabinet while articles are taken out of it or placed thereinto.

It will thus be seen that there is provided a device in which the several objects of this invention are achieved, and which is well adapted to meet the conditions of practical use.

As various possible embodiments might be made of the above invention, and as various changes might be made in the embodiment above set forth, it is to be understood that all matter herein set forth or shown in the accompanying drawings is to be interpreted as illustrative and not in a limiting sense.

Having thus described my invention, I claim as new and desire to secure by Letters Patent:

1. A cabinet having side walls, a pair of parallel horizontal supports attached to the inner

surfaces of the side walls of the cabinet, a square rack supported on said supports, each pair of opposite sides of said rack being formed with aligned notches, and means at the front ends 5 of the supports to engage within said notches, when the rack is partially withdrawn from the cabinet, said supports having means adjacent the rear ends thereof to engage the rear end of said rack when the rack is fully inserted into the cabinet, the distance between the notch engaging means and the means to engage the rear end of the rack being substantially equal to the length of said rack from front to rear.

2. A cabinet having side walls, pairs of aligned 15 horizontal rack supports on the inside of said side walls, square racks mounted on said supports, means at the front and rear ends of said supports to retain the racks against forward or rearward movement when the racks are fully inserted in the cabinet, and means at each pair of opposite sides of each of the racks to engage the means at the front ends of the supports to retain the racks against forward or rearward movement in a position where the racks are partially withdrawn from the cabinet.

3. A cabinet having side walls, pairs of aligned 20 horizontal rack supports on the inside of said side walls, square racks mounted on said supports, means at the front and rear ends of said supports to retain the racks against forward or rearward movement when the racks are fully inserted in the cabinet, and means at each pair of opposite sides of each of the racks to engage the means at the front ends of the supports to retain the racks against forward or rearward movement in a position where the racks are partially withdrawn from the cabinet, the distance between one pair of aligned supports and the next adjacent pair of aligned supports being greater than the height of the racks to permit the racks to be tilted forwardly and downwardly in partially withdrawn position, and one pair of supports serving to engage the rear ends of racks mounted on the supports below the same when in partially withdrawn position and tilted downwardly and forwardly.

4. A cabinet having side walls, a pair of parallel horizontal supports on the inside of said side walls, a square shaped rack mounted on said supports, said rack having pairs of opposite 25 walls, each pair of opposite walls being formed with aligned notches, and a pair of aligned upwardly extending lugs on said supports adapted to engage in each pair of notches.

5. A square rack having at the lower edges of 30 the side and end walls thereof, an angle shaped reinforcing frame having upwardly extending, vertical wall portions and inwardly extending, horizontal wall portions, opposite horizontal wall portions being formed with aligned pairs of notches mediate the ends thereof, adapted to coact with supporting lugs on a cabinet to support the rack in a partially extended and tilted position.

6. A rack having at the lower ends of the side 35 and end walls thereof, an angle shaped reinforcing frame having upwardly extending, vertical wall portions and inwardly extending, horizontal wall portions, opposite horizontal wall portions being formed with aligned pairs of notches mediate the ends thereof, and a cabinet having a support for said rack, and lugs adjacent the front end thereof to engage in said pairs of notches.

7. In combination, a cabinet and a square rack 40 insertable into said cabinet with either pair of

opposite sides of the rack at the front and rear of the cabinet, said cabinet having means to support said rack when the rack is inserted into said cabinet with either of its opposite side portions at the front and rear, said supporting means including means to prevent the rack from sliding forwardly or rearwardly when the rack is fully inserted within the cabinet, means on said rack adapted to cooperate with an element of the second mentioned means to support said rack in partially withdrawn position when either of its opposite side portions are disposed front and rear of the rack, to expose one part of the rack while another part of the rack is still within the cabinet.

8. In combination, a cabinet and a square rack insertable into said cabinet with either pair of opposite sides of the rack at the front and rear

of the cabinet, said cabinet having means to support said rack when the rack is inserted into said cabinet with either of its opposite side portions at the front and rear, said supporting means including means to prevent the rack from sliding forwardly or rearwardly when the rack is fully inserted within the cabinet, means on said rack adapted to cooperate with means to support said rack in partially withdrawn position when either of its opposite side portions are disposed front and rear of the rack, to expose one part of the rack while another part of the rack is still within the cabinet, and means on the cabinet to retain the rack in forwardly and downwardly tilted position when the rack is retained in partially withdrawn position.

PAUL F. KRAEFT.
